UNITED STATES PATENT OFFICE.

EBEN T. STARR, OF NEW YORK, N. Y.

IMPROVEMENT IN SKATES.

Specification forming part of Letters Patent No. 36,244, dated August 19, 1862.

To all whom it may concern:

Be it known that I, EBEN T. STARR, of the city, county, and State of New York, have invented a new and useful Improvement in Skates; and I do hereby declare that the following is a full, clear, and exact description of the same, reference being had to the accompanying drawings, making a part of this specification, in which—

Figure 1 is a side view of my invention; Fig. 2, a longitudinal central section of the same. Fig. 3 is a front view of the same.

Similar letters of reference indicate corresponding parts in the several figures.

The object of this invention is to obtain a skate which will admit of being adjusted in such a manner as to compensate for the varying height of the heels of boots and shoes, and thereby admit of the foot of the skater having a proper relative position with the skate, so as to insure ease and comfort in skating.

In order to effect this result the runner of the skate should be about parallel with the sole of the boot or shoe, and if said parts have this position with a low-heeled boot or shoe, it follows as a matter of course that with a high-heeled boot or shoe the ball or front part of the boot will be depressed, and the weight of the skater made to bear unduly on the front part of the runner. On the other hand, if the runner of the skate be parallel with the sole of a high-heeled boot or shoe, and a low-heeled boot or shoe be worn by the skater, the weight of the latter will be made to bear on the back part or heel of the runner.

To enable those skilled in the art to fully understand and construct my invention, I will proceed to describe it.

A represents the foot-stand of a skate, and B is the runner, the back part of which is secured in the heel-post C by means of a pivot, a, on which the runner is allowed to work freely. The front end of the runner is secured in the front post, D, of the foot-stand by means of a set-screw, b, which passes transversely

through post D and through an oblong slot, c, in the runner, said slot being shown in Fig. 2.

Through the central knee, d, of the runner there is made an oblong oblique slot, e, which is shown in Fig. 2, and through this slot e and the central post, E, of the runner a set-screw, f, passes, which is provided with a nut, g, which is fitted in a groove, h, at one side of the post E, (see Fig. 1,) the post E having an oblong horizontal slot, f', made through it to admit of the screw f sliding therein to suit the position of the runner and admit of the moving of the same on its pivot a.

The back, central, and front posts, C E D, of the foot-stand may be formed of pendants slotted vertically to receive the runner, (see Fig. 3,) in which the construction of the front post, D, is clearly shown.

From this description it will be seen that by relaxing or unscrewing the set-screws b f the front part of the runner may be raised or lowered so as to be parallel with the foot stand A, or have an oblique position therewith. When adjusted as represented in Fig. 1, the skate is adapted to a low-heeled boot or shoe; but when adjusted as shown in Fig. 2, with the front part brought up, the skate is adapted to a high-heeled boot or shoe.

Having thus described my invention, what I claim as new, and desire to secure by Letters Patent, is—

Having the foot-stand A made adjustable in respect to the runner B, substantially in the manner herein shown and described, so that the skate may be adjusted to boot-heels of different heights, and the runner be thus readily made to occupy a horizontal position in respect to the bottom of the wearer's foot, all as set forth.

EBEN T. STARR.
